UNITED STATES PATENT OFFICE.

GEORGE K. COOKE, OF NEW YORK, N. Y., ASSIGNOR TO D. SACKETT MOOL OF SAME PLACE.

DESIGN FOR A BADGE.

SPECIFICATION forming part of Design No. 17,867, dated November 8, 1887.

Application filed October 13, 1887. Serial No. 252,273. Term of patent 7 years.

To all whom it may concern:

Be it known that I, GEORGE K. COOKE, of the city of New York, county and State of New York, have invented and produced a new and original Design for a Badge, of which the following is a specification, reference being had to the accompanying drawing.

The drawing represents a face view of my newly-designed badge.

10 This invention relates to a design for a badge of pleasing appearance.

The leading feature of the invention consists of the representation of a cap suspended from a horse.

a represents a jockey mounted on horse having a pendant, c. This pendant passes over the upper edge of the perforated brim of cap e, suspended from the horse.

I claim as my design—

The design for a badge, consisting of representation of cap e, suspended from substantially as shown.

GEORGE K. COOKE.
